Fig. 5

Fig. 6

Fig. 7

Fig. 8

FIG. 1 is a front elevational view of a shower stall showing my new design.

FIG. 2 is a right side elevational view thereof, the left side being a mirror image of the side shown.

FIG. 3 is a rear elevational view thereof.

FIG. 4 is a top view thereof.

FIG. 5 is a cross sectional view taken on line 5—5 of FIG. 1 with the base omitted for convenience of illustration.

FIG. 6 is a fragmentary cross sectional view taken on line 6—6 of FIG. 4.

FIG. 7 is a fragmentary cross sectional view taken on line 7—7 of FIG. 5.

FIG. 8 is a fragmentary cross sectional view taken on line 8—8 of FIG. 5.

What is claimed is:

The ornamental design for a shower stall, as shown and described.
